United States Patent Office

Des. 179,675
Patented Feb. 12, 1957

179,675

SUNGLASS FRAME FRONT OR THE LIKE

Jack Bloch, Leominster, Mass., assignor to Foster Grant Co., Inc., Leominster, Mass., a corporation of Massachusetts

Application April 10, 1956, Serial No. 41,013

Term of patent 14 years

(Cl. D57--1)

FIG. 1

FIG. 2

Fig. 1 is a front elevational view of a sunglasses frame front, showing my new design; and

Fig. 2 is a top plan view thereof.

The dominant features of the design are shown in full lines in the drawing.

I claim:

The ornamental design for a sunglasses frame front or the like, substantially as shown and described.
